INJECTION MOLDING MACHINE OR THE LIKE

Arthur W. Jacobs, 5994 Columbia Road,
North Olmsted, Ohio

Filed Apr. 15, 1964, Ser. No. 79,510

Term of patent 14 years

(Cl. D54—8)

FIGURE 1 is a perspective view of an injection molding machine or the like showing my new design;

The left-hand side view not shown in FIG. 1 is the same as the right-hand side view illustrated in FIG. 3.

I claim:

The ornamental design for an injection molding machine or the like, substantially as shown and described.
